(57) **CLAIM**

The ornamental design for a chimney cap, as shown and described.

DESCRIPTION

FIG. 1 is a front perspective view of the chimney cap in use, shown mounted to a chimney of an outdoor barbecue smoker (e.g., charcoal smoker).

FIG. 2 is a front perspective view of the chimney cap.

FIG. 3 is a rear perspective view of the chimney cap.

FIG. 4 is a front elevational view of the chimney cap.

FIG. 5 is a rear elevational view of the chimney cap.

FIG. 6 is a left side elevational view of the chimney cap.

FIG. 7 is a right side elevational view of the chimney cap.

FIG. 8 is a top plan view of the chimney cap; and,

FIG. 9 is a bottom plan view of the chimney cap.

The broken lines shown in FIG. 1 are included for the purpose of illustrating environmental elements only and form no part of the claimed design.

1 Claim, 9 Drawing Sheets
